UNITED STATES PATENT OFFICE.

LEBERT E. JORDAN AND CHARLES H. BURROWS, OF MINNEAPOLIS, MINNESOTA, ASSIGNEES, BY MESNE ASSIGNMENTS, TO JORDAN MACHINE TOOL COMPANY, OF MINNEAPOLIS, MINNESOTA, A CORPORATION OF MINNESOTA.

REBORING AND GRINDING MACHINE FOR ENGINE CYLINDERS.

Application filed December 1, 1922. Serial No. 604,397.

To all whom it may concern:

Be it known that we, LEBERT E. JORDAN and CHARLES H. BURROWS, citizens of the United States, residing at Minneapolis, in 5 the county of Hennepin and State of Minnesota, have invented certain new and useful Improvements in Reboring and Grinding Machines for Engine Cylinders; and we do hereby declare the following to be a full, 10 clear, and exact description of the invention, such as will enable others skilled in the art to which it appertains to make and use the same.

This invention relates to a portable machine for boring and grinding the cylinders of an internal combustion engine and the machine is particularly adapted to be used as a reborer and grinder. The cylinders on internal combustion engines, and especially automobile engines, often get out of round due to piston wear or become cut or scored. In such cases it is really necessary to rebore and grind the cylinders to again secure a perfect fit for the pistons and piston 25 rings.

It is an object of this invention, therefore, to provide a machine of simple and efficient construction which can be easily operated and which comprises a means for reboring 30 the cylinder, as well as means for grinding the same.

It is a further object of the invention to provide such a machine having a boring bar adapted to carry a boring head, which 35 boring bar has journaled therein a grinder carrying member, said boring bar and grinder carrying member being capable of longitudinal feeding movement in two directions.

It is also an object of the invention to have said grinder carrying member disposed eccentrically in the boring bar with means for varying said eccentricity.

It is still a further object of the invention 45 to provide such a machine having a motor driven shaft and separate driving means geared to said shaft for independently driving said boring bar and said grinder carrying member respectively.

These and other objects of the invention, including the novel feeding arrangements, will be fully set forth, together with the advantages of the invention in the following

description made in connection with the accompanying drawings in which like reference characters refer to the same parts throughout the different views, and in which,

Fig. 1 is a view in side elevation of the machine;

Fig. 2 is a central vertical section taken substantially on the line 2—2 of Fig. 1, a portion of the boring bar being shown in side elevation;

Fig. 3 is a horizontal section taken substantially on lines 3—3 of Fig. 1 and Fig. 4, as indicated by the arrows;

Fig. 4 is a vertical section taken on the line 4—4 of Fig. 3, as indicated by the arrows;

Fig. 5 is a horizontal section taken on the line 5—5 of Fig. 6, as indicated by the arrows;

Fig. 6 is a vertical section taken on the line 6—6 of Fig. 5;

Fig. 7 is a horizontal section taken substantially on the line 7—7 of Figs. 1 and 8, as indicated by the arrows;

Fig. 8 is a section taken on the line 8—8 of Fig. 7, as indicated by the arrows;

Fig. 9 is a fragmentary horizontal section showing a modification of the feeding mechanism for the boring bar;

Fig. 10 is a vertical section taken on the line 10—10 of Fig. 9, as indicated by the arrows;

Fig. 11 is a bottom plan view of the boring head used;

Fig. 12 is a vertical section taken on the line 12—12 of Fig. 11; and Fig. 13 is a vertical section taken on the line 13—13 of Fig. 11.

Referring to the drawings, the machine comprises a frame having a base portion 1, which portion is finished at its lower side 95 and adapted to rest on the cylinder block of the engine. This base portion has a pedestal portion on which is mounted a suitable motor 2 shown as a conventional type of electric motor. The frame also has a 100 gearing-enclosing portion 3 and an upstanding casing portion 4 forming the upper bearings and enclosure for the boring bar. A boring bar 5 is journaled in the portion 4 of the frame, which frame will be provided 105 with suitable spaced bearings in which said

bar fits and rotates. The bar 5 is provided with a splined groove 6 extending to points adjacent each end of the bar and an annular gear or ring 7 surrounds the bar and has a tongue or key fitting in the groove 6. The ring 7 is formed at its lower portion with gear teeth 8 and thus forms a worm wheel gear and said ring is provided at points above said teeth with a pair of projecting teeth 9 for a purpose to be later described. Said teeth 8 are engaged by a worm gear 10 secured on a shaft 11 extending transversely of the frame portion 3 and journaled in suitable bearings therein, which shaft carries, adjacent one end and in the casing, a gear 12. The gear 12 meshes with and is driven by a gear 13 secured to the motor shaft 14, which shaft is shown as provided with a suitable coupling member 15 adapted to be bolted to the motor 2. It will also be noted that the gear 13 on the motor shaft 14 is provided with a grooved collar receiving a fork 53 having a handle 54 extending through the casing portion 3 and guided in a slot therein and an exterior lug thereon. By moving the handle 54, gear 13 can be moved out of mesh with gear 12 and the drive to the boring bar 5 discontinued. The shaft 11 projects at the side of the frame opposite the motor and is provided with a squared or angular shaped portion 16 adapted to receive a suitable crank or wrench by which the shaft may be turned and the boring bar thus manually rotated. The lower portion of the bar 5 is bored and threaded, as shown at 17, for the purpose of having secured therein a boring head to be later described.

The bar 5 is provided with an eccentric bore and a sleeve 18 is journaled in this bore in the bar and has its axis disposed eccentrically to the axis of the bar. A member 19 is disposed in the sleeve 18 eccentric therewith and this member has an expanded or cone shaped portion 20 at its lower end journaled in a bushing 21 secured in the lower end of sleeve 18. This portion 20 of the member 19 is also provided with a tapered socket in which the tapered shank of a grinding wheel 22 is adapted to be secured. The upper end of the bar 5 is threaded and receives a threaded sleeve coupling 23, having an inwardly extending flange extending over a collar or flange 24 formed on the upper end of sleeve 18 so that the said sleeve 18 is thus firmly supported and held in fixed relation to the bar 5, the upper end of said sleeve being substantially flush with the upper end of the member 23. The member 19 has a reduced portion 25 adjacent its upper end, at each end of which are oppositely facing conical portions 26. The lower part of the portion 25 and the lower

conical portion 26 are journaled in and contacted by the lower end of an exteriorly threaded sleeve 27 which is screwed into the top of the sleeve 18. This sleeve 27 is also interiorly threaded and receives therein another exteriorly threaded sleeve 28, in which the upper part of portion 25 and the upper conical portion 26 are journaled. The sleeves 27 and 28 are provided with angularly shaped flanges at their upper portions and jam nuts 29 are threaded thereon beneath said flanges for holding the sleeves in any fixed adjusted position. It will be seen that the sleeves 27 and 28 form a take-up device for the member 19. Said member has a shoulder portion immediately above the upper conical portion 26 which receives a link 40 to be later described and above this link, a pinion 31 is secured to the reduced end of the member 19, said pinion being surmounted by another link 40. The upper portion of the sleeve 18 is provided with teeth 32 to form a worm wheel, which teeth are engaged by a worm member 33 secured to a short shaft 34 journaled in the upper part of bar 5, and a bushing 35 threaded into said bar. The shaft 34 is provided at one end with a squared or angularly shaped portion adapted to receive a socket wrench or crank which may conveniently be inserted through an opening 36 in the casing portion 4. The eccentricity of the sleeve 18 in bar 5 is the same as the eccentricity of the member 19 relative to the sleeve 18. It will thus be seen that by turning the shaft 34 and revolving the sleeve 18, that the axis of member 19 may either be brought into concentric relation with the bar 5 or, in other words, coincident with the axis of the bar 5, or this axis of member 19 may be offset from the axis of the bar 5 a distance equal to twice the eccentricity between the sleeve 18 and bar 5.

The pinion 31 and grinder carrying member 19 are driven by a gear 37 secured on a short shaft 38 which is carried in a pair of links 39 and this shaft is connected to the upper portion of the member 19 by a pair of links 40 disposed just inside of the links 39 and immediately above and below the pinion 31. The links 39 are swingingly connected at their other ends to a shaft 41 which is journaled at its upper end in the top portion 4 of the frame and at its lower end in spaced bearings in the portion 3 of the frame. Between the links 39, a gear 30 is secured to shaft 41 and immediately above and below the links 39 are the arms of a yoke member 42. The member 42 has a portion extending downward parallel to the shaft 41 which is connected to an annular member or ring 43 surrounding the boring bar 5 and fitting in an annular recess made therein. This ring 43 has an extension 45 form-

ing a nut engaging a screw 46 to be later described and this extension 45 has a tongue 47 extending into and through a slot 48 formed in the side of the vertical portion 4 of the frame. It will also be noted that the lower arm of the yoke 42 is extended to form a support for the lower link 39, thus forming a support for the idle gear 37. By the link structure described which supports the gear 37, it will be seen that member 19 may be constantly driven and be at all times geared to the shaft 41 even though its eccentricity with respect to the boring bar 5 is changed. The shaft 41 carries a gear 49 adjacent its lower end which meshes with the gear 50 secured to the motor shaft 14, the gears 49 and 50 being illustrated as helical gears. It may be here noted the gear 50 is provided with a grooved collar receiving a fork 51 having a handle 52 extended through the casing portion 3 and adapted to slide in a slot therein and an exterior lug thereon. By moving the handle 52 longitudinally, gear 50 may be disengaged from gear 49 and the drive to the member 19 discontinued.

The screw 46 above referred to is journaled at its top portion in a bore in the upper part 4 of the frame and is journaled at its lower end in bearings in the portion 3 of the frame, as shown in Fig. 8. This screw has splined thereto adjacent its lower end, a gear 55 which gear is provided with a grooved collar 56 at one side thereof and has a sleeve extending at its other side carrying a star wheel 57 at its lower end. A short shaft 58 parallel with the screw 46 is journaled adjacent thereto in the portion 3 of the frame, as shown in Fig. 8 and this shaft has splined thereon a gear 59, which gear also has a grooved collar 60 at its upper side and a short sleeve at its lower side having a star wheel 61 at the end thereof.

The grooves and collars 56 and 60 are engaged by a block 62 having a hand lever 63 pivoted thereto, which hand lever extends through an opening in the casing portion 3 and is pivoted in lugs adjacent said opening. It will be seen that by moving the lever 63 the gears 55 and 59 will be simultaneously moved vertically. By this movement, the teeth of either star wheel 57 or 61 can be moved into alignment with the teeth 9 on the worm wheel ring 7 which is on the boring bar 5. The gears 55 and 59 and the star wheels 57 and 61 can also be moved so that the teeth 9 pass between the star wheels. It will be noted that when one of the star wheels is engaged by the teeth 9 on worm wheel 7 the screw 46 will be turned in one direction and when the points on the other star wheel are engaged by said teeth 9 the screw will be turned in the opposite direction. The screw 46 is also provided immediately above the casing portion 3 with a

beveled gear 64 which is engaged by another beveled gear 65 secured to a shaft 66 extending through the casing portion 3 and provided with a crank 67. By turning the crank handle 67, screw 46 can thus be manually turned to raise and lower the member 43 through its extension 45 which is in engagement with said screw. It will be noted that the bar 5, member 43, 42 and the parts carried thereby including the gears 37 and 30 are all moved vertically when the screw 46 is turned.

In Figs. 11 to 13, a boring head 68 is shown having a threaded sleeve 69 thereon adapted to be screwed into the threaded bore 17 of the bar 5. The member 68 is provided with a dove-tailed groove 70 in which slides and fits a portion of a wedge member 71 bored and threaded to be engaged by a screw 72 journaled in the member 68 and provided with a grooved head 85 disposed in the recess in the outer side of member 68, said screw 72 being held in place by a collar 73. The boring head is designed to use two tools 74 of dove-tailed shape which are held in place by the clamping plate 75 secured in the head by screws. The inner ends of the tools bear against the wedge portion of the member 71 and, as is obvious, can be moved outwardly by moving said wedge portion by means of the screw 72.

In Figs. 9 and 10, a modified form of shift structure is shown in the gears which operate the screw 46. In said figures, the worm wheel ring 7 having thereon one of the teeth 9 is shown. The shaft 76 is secured in the lower portion 3^a of the frame and this shaft carries a gear 77 corresponding to the gear 59 on shaft 58 in Fig. 8. The gear 77 meshes with a gear 78 and both gears are provided with hubs or sleeves disposed between the plates or arms 79 of a shifting yoke 80 which is extended through the casing 3^a in the form of a handle and has pivoted thereto, a spring pawl 81 having a portion adapted to engage in any one of three holes 82 in a boss on the side of the casing. The gears 77 and 78 also carry star wheels 83 and 84, respectively, located at different distances from said gears. When the pawl 81 engages in the middle aperture 82 the star wheels are in such position that the tooth 9 engages neither. When the pawl is in either one of the other apertures 82, however, one of the star wheels will be in position to be engaged by the tooth 9 on the worm wheel ring 7 so that the screw will be driven in one direction or the other.

It will be noted that the portion 4 of the frame adjacent the slot 48 is provided with graduations to indicate the extent of travel of the boring bar 5 and parts carried thereby.

In operation, the frame will, as stated, be placed in position on the cylinder block of

the engine. The boring bar will then be centered over one of the cylinders by the use of a centering cone or other centering means placed in the bar. When the said bar is thus centered, the frame will be firmly secured on the block and the tools 74 set a proper distance to give the desired bore of the cylinder. The motor will then be started and the boring bar and boring head driven. It will be understood that at this time the boring head is in place in the bar and the grinding wheel 22 is removed therefrom. Gears 55 and 59 will now be set so that the screw 46 is turned in the proper direction to feed the boring bar downwardly, and the clutch handle 52 will be moved to disconnect the drive for the grinder carrying member 19. The motor now being started, the boring bar will be rotated through shaft 11 and worm 10 and fed down through the cylinder so that the cylinder will be properly bored or rebored. When the boring head has traversed the desired distance into the cylinder the feed of screw 46 can be reversed by movement of the gears 55 and 59 by lever 63 and the head thus fed out of the cylinder. After the cylinder has been bored the boring head will be removed from the boring bar 5 and the grinding wheel 22 and its carrying member disposed in the member 19. The shaft 34 and worm 33 will now be adjusted to bring the edge of the grinding wheel 22 in proper relation to the bored cylinder surface to properly grind the same. Gear 50 will now be moved into engagement with gear 49 and the member 19 driven through shaft 41 and gears 30, 37 and 31. The grinding wheel 22 will thus be driven at comparatively high speed and will be carried around in proper relation to the inside of the cylinder by the slow rotation of the boring bar. The bar will, at the same time, be fed downward through the cylinder by screw 46 and the feed of the screw can be reversed at the proper time to again feed upward. The inside of the cylinder will thus be properly ground and finished. The amount of the feeding movement can, if desired, be ascertained from the graduations on the portion 4 of the frame. Any wear or looseness occurring in the lower portion 20 of the member 19 can be accurately taken up by adjustment of the sleeves 27 and 28. When it is desired to quickly raise or lower the boring head or the grinding wheel, this can be readily done by operation of the crank handle 67. As before stated, the grinding wheel 22 can be presented so that it is concentric to the boring bar, or it may be set at any intermediate position between the concentric position and its extreme position of eccentricity. After one cylinder of the engine is bored and ground, the machine can be shifted and the boring bar 5 alined

with another cylinder. After this cylinder is finished, the machine may be swung through 180 degrees and alined with the next cylinder, if desired. Such a turning movement is usually made in a four-cylinder engine, two of the cylinders being ground while the machine is in one position and two with the machine in another.

With the modified form of shift shown in Figs. 9 and 10, the star wheels for operating the screw 46 will be shifted by the yoke 80 instead of by the lever 63.

From the above description it is seen that applicant has provided an extremely simple, compact, convenient and efficient machine for operating on the cylinders of internal combustion engines. The machine is entirely self-contained and the various adjustments thereof are easily and conveniently made in a positive manner without the use of any objectionable belts. The machine is designed to be used in garages and automobile repair shops and is conveniently transportable for such use. The parts of the machine are all securely held in position and when once assembled there is no tendency for any of the parts to become disarranged.

It will, of course, be understood that various changes may be made in the form, details, arrangement and proportions of the parts without departing from the scope of applicant's invention, which, generally stated, consists in the matter shown and described and set forth in the appended claims.

What is claimed is:

1. A portable machine for grinding and boring the cylinders of internal combustion engines having in combination, a frame constructed and arranged to rest on the engine casing, and comprising bearings, a boring bar revolvable in said bearings and longitudinally movable relative thereto, a member surrounding and splined to said boring bar for turning the same, a grinding member eccentrically disposed in said boring bar, means for turning said grinding member, a screw journaled in said frame parallel to said boring bar adapted to move said boring bar and grinding member longitudinally, means driven by said member surrounding the boring bar for turning said screw in one direction, and another member driven by said means surrounding the boring bar adapted to be shifted into position to drive said screw in the opposite direction.

2. A machine for grinding and boring the cylinders of internal combustion engines having in combination, a frame, a rotatable boring bar in said frame, a sleeve eccentrically journaled in said boring bar, a grinder carrying member disposed in said sleeve, means for rotating said sleeve to vary the eccentricity of the axis of said grinder carrying member relative to the axis of said boring bar a gear secured to said grinder

carrying member, a driving shaft for said member extending parallel to said boring bar, links pivotally connected to said grinder carrying member and shaft to swing about the centers thereof, a shaft to which the other ends of said links are pivotally connected, a gear on said latter shaft and a gear on said driving shaft meshing with both of said gears whereby said gears will remain in mesh when said sleeve is turned.

3. A machine for grinding and boring the cylinders of internal combustion engines having in combination, a frame, a rotatable boring bar in said frame, a grinder carrying member movable eccentrically to said boring bar, a gear at the top of said grinder carrying member, a driving shaft for said member parallel to the axis thereof, a gear on said driving shaft, an idler gear meshing with said gears and a swinging compensating means carrying said idle gear whereby said gears will remain in mesh when said grinding member is moved eccentrically to said boring bar.

25 4. The structure set forth in claim 2, a yoke on said driving shaft embracing the ends of said links, said yoke, links and gear on said driving shaft being splined thereto and an extension on said yoke embracing said boring bar and movable therewith.

5. A portable machine for grinding and reboring the cylinders of internal combustion engines having in combination, a frame adapted to rest upon the engine casing, a 35 rotatable boring bar journaled and movable in said frame and having means at its lower end for detachably receiving a cutting tool head, a grinder carrying member eccentrically journaled in said bar, a grinder 40 removably carried by said member beneath said boring bar, means for turning said member to vary the distance between the axes of said boring bar and grinder, and means for moving said boring bar and 45 grinder in both directions vertically on said frame.

6. A portable machine for grinding and boring the cylinders of internal combustion engines having in combination, a frame 50 comprising bearings, a rotatable boring bar journaled in said bearings and longitudinally movable relative thereto, a grinder carrying member eccentrically journaled in said boring bar and rotatable therein to 55 vary the distance between its axis and the axis of said boring bar, a motor on said frame, a driving shaft driven from said motor, means for driving said boring bar from said driving shaft, and means for 60 driving said grinder carrying member from said driving shaft.

7. The structure set forth in claim 6, said means for driving said boring bar being disposed adjacent the lower end thereof, 65 and said means for driving said grinder car-

rying member being disposed adjacent the upper end thereof.

8. A portable machine for grinding and boring the cylinders of internal combustion engines having in combination, a frame constructed and arranged to rest on the engine casing, a rotatable boring bar in said frame, a driving shaft, a member surrounding said boring bar and splined thereto for rotating said boring bar driven by said driving shaft, 75 a screw journaled in said frame parallel to said boring bar, a nut member on said screw embracing said bar, and means actuated by said member surrounding said boring bar adapted to turn said screw in either direction to move the boring bar longitudinally and comprising a shiftable member.

15 9. A portable machine for grinding and boring the cylinders of internal combustion engines having in combination, a frame, 80 a rotatable boring bar in said frame, a grinder carrying member therein having its axis eccentric to the axis of said boring bar, a shaft, journaled in said frame parallel to said boring bar for driving said member, a motor shaft journaled in said frame for driving said first mentioned shaft, a shaft geared to said motor shaft, an annular gear surrounding and splined to said boring bar, and means on said last mentioned 85 shaft for driving said annular gear and boring bar.

20 10. A portable machine for grinding and boring the cylinders of internal combustion engines having in combination, a frame, a 100 rotatable boring bar in said frame, a grinder carrying member therein, having its axis parallel to the axis thereof, a motor shaft, a shaft geared to said motor shaft and extending parallel to said boring bar, and 105 geared to said grinder carrying member for rotating the same, a shaft geared to said motor shaft and to said boring bar for rotating the latter.

11. A portable machine for grinding and boring the cylinders of internal combustion engines having in combination, a frame, a rotatable boring bar in said frame, a driving shaft, an annular gear surrounding said boring bar and splined thereto driven by 110 said driving shaft, a screw extending parallel to said boring bar, means connected to said boring bar engaging said screw, a star wheel carried thereby, another star wheel 115 geared to said star wheel to rotate oppositely thereto, and means on said annular gear for contacting and rotating either of said star wheels to rotate said screw and move the boring bar longitudinally.

12. The structure set forth in claim 11, 125 and means for moving said star wheels so that either one of the same are in position to be engaged by the means on said annular gear or into position so that neither are so engaged.

13. A machine for grinding and boring the cylinders of internal combustion engines having in combination, a frame, a rotatable boring bar in said frame, a grinder carrying member having a conical portion at its lower end journaled in said boring bar, said member having oppositely disposed spaced conical portions adjacent its upper end and longitudinally adjustable means 10 contacting said conical portions respectively for taking up any longitudinal movement in said member, and maintaining said conical journals in proper position.

14. A machine for grinding and boring the cylinders of internal combustion engines having in combination, a frame, a rotatable boring bar in said frame, means encircling said bar to drive the same, a sleeve eccentrically journaled in said bar, a grinder carrying member eccentrically journaled in said sleeve means for rotating said sleeve to vary the eccentricity of said member to said boring bar, a screw for feeding all of said parts longitudinally and means driven from said first mentioned means in-

cluding a shiftable member for turning said screw in either direction.

15. A portable machine for grinding and reboring the cylinders of internal combustion engines having in combination, a frame 30 adapted to rest upon the engine casing, a rotatable boring bar journaled and movable in said frame and extending throughout the greater part of the length thereof and having means at its lower end for detachably receiving a cutting tool head, a motor disposed at the lower side of said frame and means adjacent the lower side of said frame driven by said motor for turning said boring bar, a grinder carrying 40 member eccentrically journaled in said bar, a grinder movably carried by said member below the lower end of said boring bar, and means adjacent the top of said frame for driving said grinder carrying member, and 45 also driven by said motor.

In testimony whereof we affix our signatures.

LEBERT E. JORDAN.

CHARLES H. BURROWS.
